(57) **CLAIM**

The ornamental design for an extender, as shown and described.

DESCRIPTION

FIG. 1 is a front elevation view of an extender according to the claimed design.

FIG. 2 is a rear elevation view of the extender.

FIG. 3 is a left side view of the extender, with the right side view being symmetric thereto.

FIG. 4 is a top plan view of the extender.

FIG. 5 is a bottom plan view of the extender.

FIG. 6 is a top-front perspective view of the extender.

FIG. 7 is a top-rear perspective view of the extender.

FIG. 8 is a bottom-front perspective view of the extender.

FIG. 9 is a bottom-rear perspective view of the extender.

FIG. 10 is a first perspective view of the extender in a detached configuration from a table shown in environment.

FIG. 11 is a second perspective view of the extender in an attached configuration to the table shown in environment.

FIG. 12 is a third perspective view of the extender in the attached configuration with a cushion fastened thereto shown in environment.

FIG. 13 is a fourth perspective view of the extender in the attached configuration with the cushion fastened thereto and with a patient supported and shown in environment; and, FIG. 14 is a fifth perspective view of the extender in the attached configuration with the cushion fastened thereto, and with the patient supported and the patient's feet bound and shown in environment.

The broken lines in the drawings showing the table, cushion, patient, and foot binding illustrate environmental subject matter that forms no part of the claimed design.

1 Claim, 14 Drawing Sheets
